Specification for Design.

Patented Oct. 18, 1921.

Application filed May 12, 1921. Serial No. 469,064. Term of patent 3½ years.

To all whom it may concern:

Be it known that I, AUGUST G. HILLEBRECHT, Jr., a citizen of the United States, residing at Jersey City, in the county of Hudson and State of New Jersey, have invented a new, original, and ornamental Design for an Ice-Box-Door Cleat, of which the following is a specification, reference being had to the accompanying drawings, forming a part thereof, and in which:

Figure 1 is a front elevation, and Fig. 2 a side view of an ice box door cleat embodying my new design.

I claim:

The ornamental design for an ice box door cleat, as shown.

AUGUST G. HILLEBRECHT, Jr.
